[57] CLAIM

The ornamental design for a handset telephone, as shown and described.

DESCRIPTION

FIG. 1 is a perspective view of a handset telephone showing my new design;

FIG. 2 is a front elevational view thereof;

FIG. 3 is a side elevational view thereof, the side opposite being a mirror image;

FIG. 4 is a rear elevational view thereof;

FIG. 5 is a top plan view thereof;

FIG. 6 is a bottom plan view thereof; and

FIG. 7 is a perspective view thereof with cover removed.

The cord in FIGS. 1, 3, 4, 5, 6 and 7 is shown in fragmentary form for ease of illustration.
